UNITED STATES PATENT OFFICE.

FLORA A. COLBURN, OF ROCHESTER, NEW YORK.

SHOE AND STOCKING PROTECTOR.

Application filed October 26, 1926. Serial No. 144,362.

The object of this invention is to provide a new type of gaiter or legging made up from soft and pliable rubber sheeting or rubberized material which, when slipped over the shoe and stocking, protects the stocking from being soiled by the splashing of mud and water during stormy weather.

This and other objects of this invention will be fully illustrated in the drawing, described in the specification and pointed out in the claim at the end thereof.

In the accompanying drawing:

Figure 1 is a side elevation of a shoe and stocking with the gaiter or legging being fitted thereto.

Figure 2 is a horizontal sectional view of the gaiter or legging, the section being taken on the line 2^x—2^x of Figure 1.

In the figures of the drawing like reference numerals indicate like parts.

The gaiter or legging forming the subject matter of this invention is intended to protect the shoe and stockings from having water and mud splashed against them during rainy and stormy weather. The gaiter or legging is preferably made of light soft and pliable water proof material so that a pair of them can be readily folded into a small bundle and carried in a hand bag when it is not necessary to use them. Light rubberized sheeting is ideal for the purpose because it is not only light in weight but also washable so that the gaiters can be readily cleaned by washing them off with plain water.

As illustrated in the figures the gaiter is made up of four sections 1, 2, 3 and 4. Section 1 forms the inner side of the gaiter while sections 2 and 3 form the outer side thereof. Sections 2 and 3 are fastened to section 1 at the front and back along the seams 5 and 6 which seams may be strengthened and made waterproof by the reinforcing strips 7 and 8 that are fastened over the seams and extend the lengths of these sections. Section 4 is attached to the lower end of sections 1 and 2 and forms the lower front end of the gaiter that overlaps the top of the shoe.

The middle of section 4 may be reinforced by the reinforcing strip 9 that extends longitudinally across section 4 and forms a continuation of the reinforcing strip 7. If de-

sired reinforcing strips 7 and 9 may be made as one continuous strip and thus extend from the bottom to the top at the front of the gaiter just as reinforcing strip 8 extends from the bottom to the top at the back of the gaiter.

Suitable reinforcing strips are also provided around the free edges of the gaiter at the top, bottom and sides in order to strengthen the edges of the gaiter so that they will hold their form. At the bottom sections 1 and 3 are connected by the strap 10 forming a small opening at the back of the bottom of the gaiter thru which the heel of the shoe is adapted to pass. The strap and lower portions of sections 3 and 4 are shaped so as to snugly fit the rear of the shoe when the gaiter is slipped over it.

As illustrated in the figures the free ends of sections 2 and 3 are fastened together after the heel of the shoe has been passed thru the opening formed between the strap and the rear of the gaiter. For this purpose a series of snap fasteners 11, 11 or their components are fastened along either edge of sections 2 and 3 so that these edges when brought together and folded around the stocking and over the top of the shoe are suitably fastened together.

As will be seen from an inspection of the figures the gaiter is closed on the side and the strap 10 bridges a portion of the rear of the lower end of the gaiter so that after the gaiter is placed on the shoe it fits it snugly at the bottom around the heel and prevents the gaiter from creeping up on the shoe and the stocking. The fact that the strap is located at the rear of the bottom of the gaiter also locates the gaiter with relation to the shoe as soon as the heel thereof is inserted therein.

While the drawing shows the protector fastened on the outside of the shoe, it may be made to fasten on the inside without departing from the scope of the invention.

I claim:

A shoe and stocking protector comprising a wide vertical section, a pair of narrow vertical sections fastened to said wide section one at each side thereof, an end section attached jointly to the bottom of said wide section and the first of said narrow sections, a strap permanently connecting the lower

end of said wide section and the lower end of the second of said narrow sections to form a fixed opening between said strap and the lower edges of said wide section and said second narrow section, fastening means adapted to fasten said pair of vertical narrow sections together on a vertical line be-

tween said strap on one side and said end section on the other side, with said strap snugly embracing the top of the heel of a ¹⁰ shoe over which said protector is placed to hold it firmly in place thereon.

In testimony whereof I affix my signature.
FLORA A. COLBURN.
